UNITED STATES PATENT OFFICE.

WALTER B. PAYNE, OF ROCHESTER, NEW YORK, ASSIGNOR TO TODD PROTECTOGRAPH CO., OF ROCHESTER, NEW YORK, A CORPORATION OF NEW YORK.

MOTOR-DRIVEN PRINTING MACHINE.

Application filed November 12, 1923. Serial No. 674,208.

To all whom it may concern:

Be it known that I, WALTER B. PAYNE, a citizen of the United States, residing at Rochester, in the county of Monroe and State of New York, have invented certain new and useful Improvements in Motor-Driven Printing Machines; and I do hereby declare the following to be a full, clear, and exact description of the same, reference being had to the accompanying drawings, forming a part of this specification, and to the reference numerals marked thereon.

This invention relates to motor driven printing machines of the variety, for example, adapted for printing legends such as monetary values on checks, drafts and the like, one object of the invention being to provide a practical and efficient machine of the above character comprising means for automatically regulating the speed of the motor under the variation in load produced by the intermittent connection of the motor with the machine. Another object is the provision of such a machine having an intermittent character of operation and a predetermined position of rest with means for automatically producing a differential regulation of the driving motor to correspond with the state of rest or operation of the machine. A further object is to provide in a machine of the above character having a two part separable frame, such as employed for affording access to interior portions, efficient switch means normally closed during the operation of the machine but arranged to be automatically opened by the separating movement of the frame part for stopping the motor while the parts are separated.

To these and other ends the invention resides in certain improvements and combinations of parts all as will be hereinafter more fully described, the novel features being pointed out in the claims at the end of the specification.

In the drawings:

Fig. 1 is a longitudinal sectional elevation through a motor driven printing machine embodying the present invention;

Fig. 2 is a detail elevation of resistance means employed in the motor circuit;

Fig. 3 is a sectional elevation on the line

3^a—3^a in Fig. 1 showing the motor regulating means;

Fig. 4 is a detail sectional elevation on the line 4^a—4^a in Fig. 1 showing the motor disconnected from the printing couple;

Fig. 5 is a similar view showing the motor connected to the printing couple;

Fig. 6 is a similar view showing an intermediate position of the parts;

Fig. 7 is a transverse sectional elevation of the machine substantially on the line 7^a—7^a in Fig. 1;

Fig. 8 is a detail plan view of a portion 65 of the resistance means shown in Fig. 9;

Fig. 9 is an enlarged end elevation of the resistance means as viewed from the left in Fig. 2;

Fig. 10 is a perspective view of a portion 70 of the contact means controlling the variation of resistance in the motor circuit;

Fig. 11 is a transverse sectional elevation of the machine substantially on the line 11^a—11^a in Fig. 1 and showing the frame 75 parts separated to afford access to the printing couple; and

Fig. 12 is an enlarged sectional plan view 80 on the line 12^a—12^a in Fig. 3 showing the switch means for opening the motor circuit while the frame parts are separated.

Similar reference numerals throughout the several views indicate the same parts.

The invention is embodied, in the preferred form herein disclosed by way of illustration, in conjunction with a printing machine of known variety such as disclosed in my co-pending application for Letters Patent, Ser. No. 563153 filed May 23, 1922, for printing apparatus, so that but a brief description of the same is required for present purposes.

The printing apparatus proper comprises a two part, separable frame and casing including a base part 15, Figs. 1 and 11, to which is hinged at one side, as at 16, an upper frame part 17 hereinafter termed "the casing." The base provides at its top a printing bed 18 between which and the casing 17 is a slot 19 in which the work is inserted from a table 20, Fig. 7, at one side of the machine. Journalled in the base is a shaft 21, Figs. 1 and 7, having fixed thereon spaced arms 22 between which is rotat-

ably supported a platen wheel 23 operating through a slot in the printing bed above to press the work against the type forms supported in the casing.

5 The type carrier is shown at 24 as of generally cylindrical shape with longitudinally spaced, circumferentially extending type forms 25 for cooperation individually with the platen wheel 23. The type carrier is 10 splined on a main shaft 26 journaled at its end in the part 17 and it is apparent from this construction that the type carrier may be shifted longitudinally on shaft 26 to bring the type forms selectively to position 15 for cooperation with the platen, after which the carrier may be rotated by rotation of the main shaft to print and feed the work. The operation of the machine thus involves an alternate relative type selecting movement of the printing couple with shaft 26 stationary and a rotary printing movement of the couple to impress and feed the work therebetween effected by rotation of the main shaft 26.

20 The type selecting movement is effected by manual means comprising a yoke 27 having spaced arms 28 and 29 embracing the ends of the carrier and slidably and rotatably engaged with the main shaft. An arm 30, Fig. 7, projects from the yoke through a slot in the casing and carries an index 31 cooperating with a dial 32 on the casing marked with the type forms on the carrier. Fixed to the arm and yoke also is a handle 33 for sliding 25 the carrier in accordance with the dial to select the type, and also for rocking the yoke through a small angle about the main shaft for a purpose presently to be described. Inking rolls for the type are shown at 34 30 rotatably supported on yoke 27.

35 Means are provided through which the rocking movement of handle 33 and the yoke, imparted after the selection of each type form serves to connect to the main shaft a continuously driven electric motor 40 of any suitable variety mounted as shown on one end of the casing. This mechanism comprises a lug 36 on yoke 27 adapted in the 45 rocking movement of the latter to engage a bail 37 fixed on a shaft 38 rotatably supported by any suitable means on the frame and projecting through one end of the latter into an end compartment indicated generally at 39. The end of the shaft is here provided with an arm 40 fixed thereon and carrying a pivoted spring actuated lever 41. One arm 42 of this lever is shaped to engage an arm 43 of a spring actuated lever 44 50 pivotally supported on the casing and having an arm 45 adapted in one position to engage the end 46 of a dog 47 pivotally supported on a disc 48 fixed on the main shaft. Lever 41 has also an arm 49 arranged to be 55 engaged and swung by the hub portion of dog 47 during the rotation of the disc 48

with the main shaft as shown in Figure 6. At 50 is a toothed portion of a sleeve 51 rotatably carried on the main shaft and provided with a gear 52 meshing with a pinion 53 continuously driven by the motor 76 as hereafter described. A spring 54 tends to swing dog 47 to bring a lug 55 thereon into engagement with one of the teeth of member 50 for connecting the latter with the main shaft and thereby rotating the same 75 and the printing couple to effect a printing operation. Dog 47 however is normally held out of engagement with member 50, as shown in Fig. 4 by the contact of its end 46 with lever 44, a spring actuated pawl 56 80 serving in cooperation with a shoulder 57 on the disc to prevent reverse movement of the latter. It is apparent, however, that the rocking movement of shaft 38, effected by the depression of handle 33, tends to move 85 lever 41 to swing lever 44 out of the path of dog 47, as shown in Fig. 5. When thus released the dog is moved by its spring into engagement with the rotating toothed member 50 and the main shaft is thereby rotated. 90 As dog 47 reaches lever arm 49, however, it swings lever 41 out of engagement with lever 44, as shown in Fig. 6, so that the latter returns to initial position and at the end of one complete revolution of the main shaft 95 engages and detaches dog 47 from the rotary member 50 and again brings the main shaft and printing couple to rest for the selection of the next type form to be printed.

100 The motor is connected with the toothed member 50 by means comprising a flexible coupling 58 of any suitable variety between its shaft and a shaft 59 supported in suitable bearings on the frame. Fixed on shaft 59 is a worm 60 meshing with a worm wheel 61 on a downwardly extending shaft 62 carrying at its lower end the pinion 53 previously referred to as driving sleeve 51, the above parts being shown and described in detail in my said copending application. 105

110 It is evident from the above description that the printing couple is intermittently connected with and disconnected from the continuously rotating motor so that the latter is alternately loaded and allowed to rotate idly. The operation of the printing couple, especially where the printing surfaces are corrugated or otherwise formed for breaking the paper, as commonly the case in machines of this variety, and also when a heavy quality of paper is printed, imposes a substantial load on a motor of the small size and power necessitated by the limits of size and weight in apparatus of this character and a motor suitably designed and energized for operating the printing couple, tends to rotate at an excessive speed, or in other words to "race," while idling between successive applications of the load. It has 115 been found that this difficulty may be ad- 120 125 130

vantageously overcome by an automatic variable electric control of the motor speed. The invention accordingly provides means for automatically operating an electric speed regulating apparatus for the motor, connected with the printing couple and thus controlled by the mechanism connecting the latter to and disconnecting the same from the motor or in other words by the operating handle 33 of the machine. Such means comprises a resistance element automatically included in the motor circuit to reduce the impressed voltage at the instant of disconnection of the printing couple from the motor and to remove the resistance at the beginning of each printing operation.

The resistance means is mounted in the base part of the frame and constructed as presently to be described, connection being made therewith through a pair of conductors 63 and 64, Fig. 3 leading upwardly from the base to the automatic device for including the same in and removing it from the motor circuit which device will now be described.

Fixed on the main shaft is a drum 65, Figs. 1 and 10, of insulating material the circumference of which carries a ring of conducting metal 66 having a gap or opening 67. Engaging the circumference of the drum are a pair of spaced brushes 68 and 69 sliding longitudinally in stationary insulated conducting bearings 70 and 71 and maintained in contact with the drum by the action of springs 72, as well understood in the art, these parts being so constructed and arranged that in the position of rest occupied by the printing couple between printing movements, brush 68 engages insulating material in the gap 67 of body 65 out of contact with the ring 66 which however is engaged by the other brush. The conductors 63 and 64 are connected respectively with the holders of brushes 68 and 69. From the brush 68 a conductor 73 leads to one side of the supply line 74 while a conductor 75 connects the other brush 69 with the motor. From the other terminal of the latter a conductor 76 leads to a manually operable switch 77 of any suitable variety, the other terminal of which is connected by a conductor 78 with the other side of the line. It is apparent from the construction of this device and its connections that while the motor is disconnected from the printing couple in the stationary condition of the latter, the resistance means in the base of the machine is included in the motor circuit to reduce the impressed voltage and the idle speed of the motor. At the instant of connection of the motor with the printing couple, however, the rotation of drum 65 brings both brushes into contact with its conducting ring 66 which shortcircuits the resistance means and thus applies the full line voltage to the motor as the latter receives its load. At the end of each printing operation the parts return to the initial position shown in Fig. 3 in which the printing couple is disconnected and the load removed from the motor the speed of which is therupon maintained substantially constant by the inclusion of the resistance in its circuit as already described.

The resistance means is, in the present instance, a cylindrical coil 79, Figures 1 and 9 of suitable wire or other resistance material, the coil being supported at its ends by bracket 80 on the base. The coil is tapped at a plurality of longitudinally spaced points and such taps connected with contacts 81 supported in and projecting through a bar of insulating material 82 parallel with the coil mounted at its ends in extensions 83 of the end brackets. Slidably supported on the bar in any suitable manner is a shoe 84, Figures 8 and 9 of conductive metal provided with a spring contact 85 arranged to engage successively and individually with the contacts 81 as the shoe is slid longitudinally of the coil. The shoe is connected through a safety switch means described below with one of the conductors 63 or 64, while the other of these conductors is connected as at 85, Fig. 2 with one of the end taps of the coil. Shoe 84 may be conveniently adjusted as described, therefore, to vary the amount of resistance employed, as conditions may require, to compensate for the variation in load on the motor and maintain its speed constant.

Another advantageous feature of the present invention is found in the provision of safety means for automatically breaking the motor circuit whenever the frame portions, or base and upper casing, are swung apart, as illustrated in Fig. 11 for the purpose of obtaining access to the interior thereof, without first stopping the motor by operating switch 77. The machine is opened of course, only between printing operations, and therefore while the resistance means in the base is connected in series with the motor circuit. Interruption of the circuit through the resistance means therefore serves to stop the motor, and for automatically accomplishing this result conductors 63 and 64 are connected with the resistance through the terminals of a switch part indicated generally at 86 in the bottom of the casing compartment 39 which depends, as shown in Fig. 1, opposite an end of the base. This switch part comprises spaced insulated terminals 87 and 88 fixed therein and extending exteriorly of the casing toward the base for contact respectively, in the closed position of the frame, with a pair of contacts 89 and 90 in a cooperating switch part 91 projecting oppositely through the end wall of the base. These latter contacts are

preferably spring actuated as shown toward the fixed contacts 87 and 88 to insure electrical connection therebetween when the frame parts are in closed position. Contacts 89 and 90 are connected as described with the resistance means and it is apparent from this construction and its connections that whenever the frame parts are separated the motor circuit is automatically broken and the motor stopped until such time as the frame parts are returned to operating position, when the circuit is automatically reestablished. The invention thus provides in combination with printing apparatus of the character described a thoroughly practical and efficient apparatus for automatically regulating the driving motor to at all times maintain its speed substantially constant, which apparatus is controlled automatically by the normal operating means of the printing machine. The apparatus likewise provides reliable safety means for automatically stopping the motor whenever the machine frame is open and thereby avoiding possible injury to the mechanism or to the operator.

I claim as my invention:

1. The combination with a printing machine of a continuously driven electric motor therefor, mechanism for alternately connecting said motor to and disconnecting it from said machine to effect intermittent operation of the latter, and electric speed regulating apparatus for said motor operated automatically by said mechanism to compensate for the intermittent application of load thereto.

2. The combination with a printing machine, of an electric motor for driving the same, power supply means connected with said motor for driving the latter continuously, mechanism for alternately connecting said motor to and disconnecting it from said machine to effect intermittent operation of the same, resistance means for inclusion in the motor circuit, and a device operated automatically by said mechanism for varying the amount of resistance in said circuit and regulating the motor speed under the alternating application and removal of load.

3. The combination with a printing machine, of an electric motor for driving the same, power supply means connected with said motor for driving the latter continuously, mechanism for alternately connecting said motor to and disconnecting it from said machine to effect intermittent operation of the same, resistance means for inclusion in the motor circuit, and contact means connected with and driven by said machine for varying the amount of resistance in said circuit and regulating the motor speed under the application and removal of load.

4. The combination with a printing ma-

chine, of an electric motor for driving the same, power supply means connected with said motor for driving the latter continuously, mechanism for alternately connecting said motor to and disconnecting it from said machine to effect intermittent operation of the same, resistance means for inclusion in the motor circuit, and a device comprising brushes and rotary contact means connected with and rotated by said machine for varying the resistance in said circuit and regulating the motor speed under the application and removal of load.

5. The combination with a printing machine, of an electric motor for driving the same, power supply means connected with said motor for driving the latter continuously, mechanism for alternately connecting said motor to and disconnecting it from said machine to effect intermittent operation of the same, resistance means and a device operated automatically by said mechanism for including said resistance means in the motor circuit while the motor is disconnected from the machine to regulate the idle speed of the motor.

6. The combination with a printing machine, of an electric motor for driving the same, power supply means connected with said motor for driving the latter continuously, mechanism for alternately connecting said motor to and disconnecting it from said machine to effect intermittent operation of the same, resistance means and a device comprising brushes and a rotary contact means connected with and rotated by said machine for including said resistance means in the motor circuit while the motor is disconnected from the machine to reduce the idle speed of the motor.

7. The combination with a printing machine comprising a type carrier and platen having alternately a relative type selecting movement and a relative printing movement, manually operable means for effecting said selecting movements, a continuously driven motor, mechanism for intermittently connecting said motor to and disconnecting it from said machine to effect said printing movements, an electric speed regulating apparatus for said motor, and a device for intermittently connecting said apparatus in the motor circuit connected with said machine and operated automatically by said printing movements thereof.

8. The combination with a printing machine comprising a type carrier and platen having alternately a relative type selecting movement and a relative printing movement, manually operable means for effecting said selecting movements, a continuously driven motor, mechanism arranged for operation by said manual means for intermittently connecting said motor to and disconnecting it from said machine to effect

said printing movements thereof, resistance means, and a contact device for intermittently connecting said resistance means in the motor circuit and connected with said machine for operation automatically by said printing movements thereof.

9. The combination with a printing machine comprising a printing couple having alternately a rotary printing movement and a relative type selecting movement, a rotary shaft for effecting said printing movements, a continuously driven electric motor, mechanism for intermittently connecting said motor to and disconnecting it from said shaft, resistance means, a pair of brushes, a contact ring carried by said shaft in cooperation with said brushes, and connections between said brushes, resistance and motor arranged to include said resistance means in the motor circuit between said intermittent printing movements.

10. The combination with a printing machine comprising a two part separable frame and a printing couple carried thereby by having an intermittent printing movement, a continuously rotating electric motor mechanism for intermittently connecting said motor to and disconnecting the same from said printing couple to effect said printing movements, resistance means for the motor circuit, a contact device operated by said printing couple to automatically vary the resistance in said motor circuit and regulate the motor speed under the application and removal of the load, and normally closed switch means in the motor circuit arranged to be opened by the separating movement of said frame parts for automatically stopping the motor while said parts are separated.

couple, and switch means in the motor circuit arranged to be opened automatically by a separating movement of said frame parts for stopping the motor while said parts are separated.

11. The combination with a printing machine comprising a two part separable frame and a printing couple carried thereby by having an intermittent printing movement, a continuously rotating electric motor mechanism for intermittently connecting said motor to and disconnecting the same from said printing couple to effect said printing movements, resistance means for the motor circuit, a contact device operated by said printing couple to automatically vary the resistance in said motor circuit and regulate the motor speed under the application and removal of the load, and normally closed switch means in the motor circuit arranged to be opened by the separating movement of said frame parts for automatically stopping the motor while said parts are separated.

WALTER B. PAYNE.
